UNITED STATES PATENT OFFICE.

LEOPOLD L. LANGROCK AND JOSEPH H. LANGROCK, OF NEW YORK, N. Y.

DESIGN FOR A PILLOW-COVER.

No. 39,162.

Specification for Design.

Patented Feb. 25, 1908.

Application filed December 4, 1907. Serial No. 405,129. Term of patent 3½ years.

To all whom it may concern:

Be it known that we, LEOPOLD L. LANGROCK and JOSEPH H. LANGROCK, citizens of the United States, residing in the borough of Manhattan, city, county, and State of New York, have invented a new, original, and ornamental Design for a Pillow-Cover, of which the following is a specification.

The nature of our design is fully represented in the accompanying drawing, to which reference is made and which shows in elevation, a pillow cover embodying our design.

We claim,

The ornamental design for a pillow cover, as shown.

LEOPOLD L. LANGROCK.
JOSEPH H. LANGROCK.
